UNITED STATES PATENT OFFICE

JOHN ALLEN HEANY, OF NEW HAVEN, CONNECTICUT, ASSIGNOR TO SIRIAN LAMP COMPANY, OF NEW HAVEN, CONNECTICUT, A CORPORATION OF DELAWARE

ELECTRIC LIGHT BULB AND METHOD FOR MANUFACTURING SAME

Application filed September 8, 1926. Serial No. 134,218.

This invention relates to the manufacture of tipless electric light bulbs and particularly to the manufacture of stems for such bulbs through which the air must be exhausted from the bulb, and by means of which the lead in wires are connected to the lighting filament in the bulb.

In the manufacture of tipless electric light bulbs, it is necessary to exhaust the air through the stem of the bulb and to accomplish this, an exhaust tube is provided which is fused to the stem. Great difficulty has been experienced in fusing the exhaust tube to the stem, and at the same time maintaining the opening through the tube. To keep the opening through the exhaust tube open, air is sometimes directed through the tube during the fusing process or the tube is sometimes filled with a substance which will crumble in the action of heat so that it may be shaken or washed from the tube after the fusing process is completed.

One of the objects of this invention is to provide a method of manufacturing tipless electric light bulbs which will maintain the opening through the exhaust tube during the fusing process in a simple and less expensive manner than has been heretofore used. Another object of the invention is to provide an exhaust tube for a stem for a tipless electric light bulb which has been reinforced against a collapse during the fusing process. Another object of the invention is to provide a reinforcing member for the exhaust tube of a tipless electric light bulb which will prevent the tube from collapsing during the fusing process and which will give with the expansion and contraction of the tube to eliminate undue strains in the glass and possible fracture thereof. Other objects of the invention will be apparent as the description thereof proceeds.

Referring now to the drawings in which an embodiment of my invention has been illustrated:

Fig. 1 is a front elevation of the stem as the parts are arranged before the fusing process;

Fig. 2 is a front elevation of the stem after the fusing process;

Figs. 3 and 4 are perspective views of two embodiments of the reinforcing member;

Fig. 5 is a front elevation of a stem adapted to be used in a different form of electric light bulb;

Fig. 6 is a side view of the stem shown in Fig. 5;

Fig. 7 is a side elevation of a machine in which the stem may be made, parts being broken away for purpose of illustration;

Fig. 8 is a front view of the machine shown in Fig. 7;

Fig. 9 is an enlarged sectional elevation of a portion of the machine showing the tubes held therein; and

Fig. 10 is a plan view of the clamps for holding the tubes in position.

Referring now more specifically to the drawings, my improved stem comprises a stem tube 10 into which is inserted an exhaust tube 11 and lead in wires 12. A reinforcing member 13 comprising a sleeve having a slot 14 extending from end to end on one side thereof is inserted in the tube 11 and may be held in the desired position therein by a slight indentation 15 formed in the side of the exhaust tube 11, or if desired, may be held in position by another method to be hereinafter described. The reinforcing member may be made of any material which is non-fusible at the fusing temperature of glass or it may also be formed of a coil of wire 16, Fig. 4.

The stem tube 10, exhaust tube 11 and wires 12 may be supported in position shown in Fig. 1, the tubes heated and the sides of the lower end of the stem tube pressed in fusing the two tubes together and forming a flat mass of glass 17 which closes the end of the stem tube and seals the lead in wires therein. The reinforcing member 13 prevents the glass of the exhaust tube 11 from collapsing when it is heated to the fusing temperature and when the sides of the stem tube are pressed against it.

The stem as shown in Figs. 1 and 2 is adapted to be used in large electric light bulbs, the end 18 of the exhaust tube forming a support for the lighting element or filament 18a of the bulb. After the stem has

100

been completed, as shown in Fig. 2, the filament is added and the stem and filament inserted in a bulb 19 having a rounded tipless end, and the bulb and stem fused together at 20 in a manner well known to the art.

5 The stem shown in Figs. 5 and 6 is adapted to be used in small electric light bulbs which do not need a support for the lighting filament. In this case the exhaust tube 11 is cut off at 21 adjacent the end of the reinforcing member and serves only to provide an opening into the interior bulb through which the air may be exhausted.

10 The method of manufacturing this improved stem is best carried out by the use of the machine shown in Figs. 7 to 10. A plurality of these machines are mounted on a spider, one arm 22 of which is shown in Fig. 1. The end of the arm 22 has a sleeve 23 rotatably mounted therein upon the lower end of which is mounted a gear 24 and to the upper end of which is attached the standard 25 by means of the set screw 26. The gear wheel 24 meshes with the gear 27 which is driven by a motor (not shown) which causes the sleeve 23 and the standard 25 to rotate about the axis of the sleeve 23. A pair of rods 28 are rotatably mounted in lugs 29 and 29a formed integral with the standard 25 and a pair of clamp arms 30 are attached to the upper end of the rods 28. The clamp arms 30 are urged toward each other by spring 31 and are adapted to hold the exhaust tube 11 between their ends, notches 32 being provided therein to accommodate the tube. Spaced a little lower down on the rods 28 are a second pair of clamp arms 33 which are attached to the rods 28, one to each rod, and which are adapted to support the stem tube 10 between the ends thereof, notches similar to those in the arms 30 being provided to fit around the sides of the stem tube. Arms 34 are provided at the bottom of the rods 28, one arm being attached to each rod and a spring 35 is disposed between the arms 34 to urge them apart. The arms 34 may have rounded ends 36 to facilitate the grasping between the fingers, and when the arms are so grasped and squeezed together, the clamp arms 30 and 33 are caused to open so that the tubes 10 and 11 may be inserted or removed therefrom.

15 A cup 37 is adjustably supported from the standard 25 by means of a post 38 and a set screw 39. The cup 37 has an opening 40 in the bottom thereof through which the exhaust tube 11 is adapted to fit, the bottom of the cup being larger than the opening 40 to provide a shelf upon which the lead in wires 12 are adapted to be rested before the tubes 10 and 11 are fused together.

20 A sleeve 41 is slidably mounted within the sleeve 23 by means of a key 41a and is adapted to be reciprocated therein by means of a lever 42 which is pivoted at 43 to an

25 arm 44 integral with the arm 22 of the spider and the other end of which is bifurcated and engages a spool 45 attached to the lower end of the sleeve 41. A pair of arms 57 having fingers 57a are pivoted to the standard 25 by screws 58 and are pivotally connected to the upper end of the sleeve 41 by screws 60. When the sleeve 41 is raised by means of the lever 42, the fingers 57a on the arms 57 are brought together against the stem tube 10, pressing the stem tube against the exhaust tube.

30 A shaft 46 is disposed within the sleeve 41 and is held rigidly with relation to the standard 25 by a clamp 47 integral with the standard 25. The shaft 46 may be raised or lowered in the clamp 47 and held in adjusted position by the set screw 48. A cup 49 is threaded on to the upper end of the shaft 46 and is adapted to be held firmly thereon by means of the thumb screw 50. This cup is adapted to receive and support the lower end of the exhaust tube 11. If desired a wire 51 may be slidably mounted in a hole 52 in the shaft 46 passing upwardly through a hole 53 in the cup 49 and up through the tube 11 for the purpose of supporting the reinforcing member 13 therein. The hole 53 in the shaft 46 opens out into a slot 54 and the lower end of the wire 51 is bent outwardly to form a handle 55 by which the wire may be raised and lowered to any desired position with relation to the tube 11. The wire may be held in its adjusted position by means of a thumb screw 56 in the side of the shaft 46.

35 In the operation of the machine, a flame is directed against the tubes by the burner 61, the tubes, together with the standard being rotated at the same time by the gear 27. When the tubes have been heated to a fusible temperature, the lever 42 may be depressed which brings the arms 57 and fingers 57a together and fuses the stem tube 10 against the exhaust tube 11 and seals the wires therebetween, forming the flat mass of glass 17. The machine is then stopped and the tubes released by pressing the arms 34 whereupon the finished stems may be removed from the machine. If the indentations 15 are provided in the exhaust tube 11 as shown in Fig. 1, it is not necessary to use the rod 51, such indentations acting to support the reinforcing member.

40 It will be evident from the above description that I have provided an inexpensive and simple method of maintaining the opening through the exhaust tube of a tipless electric light bulb without the use of expensive air blasts or other well known methods, my simple reinforcing member being adapted to remain in the stem and to become a part of the finished bulb.

45 Many modifications of the stem shown in the drawings, may be resorted to without

departing from the spirit of the invention, and I do not therefore desire to limit myself to the embodiments shown, but to interpret the invention broadly within the scope of the appended claims:

5 Having described my invention what I claim and desire to secure by Letters Patent is:

- 10 1. The method of making a tipless electric lamp which comprises providing an element supporting glass tube through which the lamp is adapted to be exhausted; forming a slight indentation in said tube; inserting a hollow reinforcing member into said tube to rest upon said indentation; inserting said tube together with lead in wires into a larger globe supporting glass tube; and simultaneously fusing said tubes together adjacent said reinforcing member and sealing said lead in wires therebetween.
- 15 2. A stem for tipless electric bulbs comprising a stem tube closed at one end; an exhaust tube spaced within said stem tube extending beyond each end thereof and integral with and supported by the closed end of said stem tube; and a resilient reinforcing member within said exhaust tube adjacent the closed end of said stem tube to maintain at all times an opening through said exhaust tube, said resilient member being in the form of a tube with an axial slot extending from end to end thereof.
- 20 3. A stem for tipless electric bulbs comprising a stem tube closed at one end; an exhaust tube extending through said stem tube beyond the ends thereof and integral with and supported by said closed end thereof; and a reinforcing sleeve having a slot extending from end to end along one side thereof within said exhaust tube at the point where said exhaust tube passes through the closed end of said stem tube.
- 25 4. A stem for tipless electric bulbs comprising a stem tube closed at one end; an exhaust tube placed within a stem tube and extending beyond each end thereof and integral therewith at said closed end; a reinforcing member of non-fusible material within said exhaust tube at the point of fusion with the said stem tube, whereby a permanent opening through the exhaust tube is maintained; and positive means within the exhaust tube for preventing axial movement of the reinforcing member in one direction.

55 In testimony whereof, I affix my signature.
JOHN ALLEN HEANY.
